Primary Examiner — Cynthia Ramirez*Assistant Examiner* — Xavier Marti-Santos(74) *Attorney, Agent, or Firm* — Headland Law & Strategy; Matthew J. Smyth(57) **CLAIM**

The ornamental design for a placemat, as shown and described.

DESCRIPTION

FIG. 1 is a perspective view of a placemat showing our new design;

FIG. 2 is a left-side view thereof;

FIG. 3 is a right-side view thereof;

FIG. 4 is a front-side view thereof;

FIG. 5 is a rear-side view thereof;

FIG. 6 is a top view thereof; and,

FIG. 7 is a bottom view thereof.

The broken lines in the figures are for the purpose of illustrating portions of the placemat, which form no part of the claimed design.

1 Claim, 5 Drawing Sheets(56)
